(57) **CLAIM**

The ornamental design for a lighting apparatus (lighting apparatus), as shown and described.

DESCRIPTION

FIG. 1 is a front perspective view of a lighting apparatus (lighting apparatus) according to the present design;

FIG. 2 is a top perspective view of

FIG. 3 is a rear perspective view thereof;

FIG. 4 is a rear bottom perspective view thereof;

FIG. 5 is a front view thereof;

FIG. 6 is a rear view thereof;

FIG. 7 is a right side view thereof;

FIG. 8 is a left side view thereof;

FIG. 9 is a top plan view thereof;

FIG. 10 is a bottom plan view thereof;

FIG. 11 is a cross-sectional view along the lines 1-1 as
shown in FIG. 6,

FIG. 12 is a cross-sectional view along the lines 2-2 as
shown in FIG. 6,

FIG. 13 is a cross-sectional view along the lines 3-3 as
shown in FIG. 6,

FIG. 14 is a cross-sectional view along the lines 4-4 as
shown in FIG. 6; and,

FIG. 15 is a plan view of the lighting apparatus in use in a
ceiling.

The portions shown in broken lines do not form part of the
claimed design.
